UNITED STATES PATENT OFFICE.

FRANK McMURRAY SAWYER, OF LOS ANGELES, CALIFORNIA.

METHOD OF MAKING ARTIFICIAL BUILDING BLOCKS.

Application filed January 12, 1920. Serial No. 350,802.

To all whom it may concern:

Be it known that I, FRANK McMURRAY SAWYER, citizen of the United States, residing at Los Angeles, in the county of Los

5 Angeles and State of California, have invented certain new and useful Improvements in Methods of Making Artificial Building Blocks, of which the following is a specification.

10 This invention relates to improvements in apparatus and method of making artificial building blocks or slabs, particularly slabs provided with grooved edges and sunken panels.

15 One of the particular objects of the invention, is to provide a means for casting or molding artificial slabs in a rapid and efficient manner at a minimum of cost, and at the same time avoid the handling of uncured products, and utilizing only a limited amount of floor space for the purpose.

20 Another important object of the invention is, to provide a molding means in which the slabs are cured in dense formation and under a condition wherein air is excluded during the curing process, excepting possibly a very small amount which might enter around the edges of the molding means.

25 These and other objects hereinafter set forth are attained by the means illustrated in the accompanying drawing, in which:—

Fig. 1 is a vertical sectional view through a pile of slabs and their molding forms showing one step of the improved method.

30 Fig. 2. is a view similar to Figure 1 showing another step in the improved method.

Fig. 3. is a horizontal section on the line 3—3 of Figure 1.

Fig. 4. is a perspective view of one of the 40 core frames.

Fig. 5, is a perspective view of one of the finished slabs looking at the underside thereof, and

Fig. 6 is a perspective view of one of the 45 molding frame or forms.

Similar reference numerals in all of the figures of the drawing designate like parts.

The main idea of this improved method is to avoid the expensive system of handling 50 green concrete products in the manner now ordinarily practiced, and to allow the slabs to cure in dense formation by excluding practically all air while curing. The improved method is as follows:—

55 Starting on a smooth floor or substantial platform, a form 10 for molding a single

slab is placed in position thereon. This form is then filled level with concrete and floated to the form, then after the concrete has set sufficiently, a sheet of oil paper 11 (or other material which is non-adhesive with respect to the slab-material) is laid over the face of the slab, and then another form 10 is placed in position on the top of the first mentioned form, filled and floated with concrete material, and after setting another sheet of oil paper is placed upon the top, and so on until the pile of slabs so formed reaches a height too high to work conveniently. It is of course understood 60 more than one pile can be started at the same time.

As fast as the concrete thoroughly sets in the lowermost slabs, the forms are removed therefrom and used for forming the 70 slabs at the top of the pile, thus the lowermost slabs are utilized as supports for molding the upper slabs, thereby avoiding the necessity of moving the partly cured slabs from one place to another in order to secure a smooth support for forming another slab. It being understood that the lower forms are not removed until after the concrete 75 therein is set sufficiently to retain their shape and able to support the weight of the slabs and forms placed above the same. In this manner the slabs are practically cured in sealed chambers formed between the walls of the molds and the oiled paper, and consequently they cure in dense formation without air holes, thereby forming smooth and 80 strong slabs.

In certain constructions it is desirous of 85 using relatively thick slabs which are of relatively light weight so that they can be handled easily. For these conditions a sunken panel slab is formed, such as shown in the drawing. It being a part of the present method to form this sunken panel, the operation is described as follows:

When the molding form 10 is placed in position, a form 12 is placed centrally therein. This form 12 is preferably constructed of very thin metal and has both ends open, and is of less height than the thickness 100 of the slab to be cast. After mold 12 is placed in position it is filled and packed with damp sand, and then some of the slab material is poured around the same, preferably to the top thereof, and at this time the form 12 is withdrawn and the slab material poured in to fill the form 10 and the 105 110

paper applied as before described. It is obvious that the sand remains in place until the slabs are cured.

In other certain constructions it is desirous of using slabs having grooves around their edges, in which event the forms or molds 10 are provided with ribs 13 extending entirely around the mold on its inner side and shaped to the contour of the groove desired. To provide for the removal of the forms or molds from the cured grooved slabs, the molds are preferably formed of half sections 14, and are provided at the joint of the sections with any suitable locking means, such as the hooks and bolts shown in the drawing. After the locking means is unfastened, the sections of the mold are withdrawn laterally, as indicated in dotted lines in Figure 3 of the drawing. Thus 20 is provided a mold which can be withdrawn from the bottom grooved slabs of a pile in the course of formation, so that it can be used in another portion of the pile. The sides of the mold are preferably formed of 25 three pieces to prevent warping.

With this method one slab can be molded

upon another in a few minutes, and when a semi-dry mixture is used the operation can be continuous. Oil paper has been found to be the best dividing means to be used 30 between the slabs, but when the slab material is allowed to set sufficiently, oil can be applied for the purpose of dividing the slabs.

Having thus fully described the invention, 35 what is claimed is:—

The method of molding artificial building slabs having a central depressed portion, consisting of placing a slab-form on a base, next placing a hollow core-form centrally therein and filling the core-form with core-forming material, next filling the slab-form anterior of the core-form up to the height of the core-form with slab material, then withdrawing the core-form while the 40 slab material is soft leaving the sand core lying within the slab material, and finally filling the slab-form over the sand core and then allowing the slab to cure before the 45 removable of the slab-form and sand-core. 50

In testimony whereof I affix my signature.

FRANK McMURRAY SAWYER.
